UNITED STATES PATENT OFFICE.

GEORG SZIMAY, OF BUDA-PESTH, AUSTRIA-HUNGARY.

MULTIPLE-CYLINDER AIR-COMPRESSING ENGINE.

SPECIFICATION forming part of Letters Patent No. 642,386, dated January 30, 1900.

Application filed October 14, 1898. Serial No. 693,532. (No model.)

To all whom it may concern:

Be it known that I, GEORG SZIMAY, a subject of the Emperor of Austria-Hungary, residing at Buda-Pesth, Austria-Hungary, have 5 invented a certain new and Improved Multiple-Cylinder Air-Compressing Engine, of which the following is a full, clear, and exact description.

The present invention relates to multiple-cylinder air-compressing engines; and the object is to increase the efficiency of the same, at the same time rendering the construction as simple as possible.

The invention consists, essentially, in the 15 peculiar combination of four cylinders and their suction and pressure connections, as hereinafter set forth, and particularly pointed out in the claims, and in order to render the present specification more easily intelligible reference is had to the accompanying drawings, in which similar letters of reference denote similar parts throughout the several views.

Figure 1 is a side elevation of the engine, 25 showing two of the valves in section. Fig. 2 is a plan view, and Fig. 3 a detail longitudinal section through the mechanism for positively operating two of the valves.

The four cylinders $c c' c' c$ are arranged in 30 pairs on the bed-plate f , each pair having the cylinder-glands and stuffing-boxes opposite each other and being provided with a common piston-rod c^2 . These are again rigidly coupled by means of the cross-pin c^3 , on which 35 the fork g' of the connecting-rod g engages. The other end of the connecting-rod g is attached to the crank s^2 of the crank-shaft s' , which is mounted in bearings $l l$ at the forward end of the bed-plate f and provided with 40 a fly-wheel s and a large chain-wheel z' . This latter is connected by means of a chain z^2 with a small chain-wheel z , fast on a shaft a' , mounted in bearings l' , parallel to the shaft s' and being turned either by hand by means 45 of the handle h of the wheel a or by machine-power by means of the pulley r . Each cylinder is provided with two outlets n , one at either end of the same, for pipe connections, and the said cylinders are connected up in 50 the following manner:

For the convenience of the present specification the stuffing-box end of each cylinder

will be called the "forward" end and the other the "rear" end. The rear ends of the two cylinders $c c$ are connected by a pipe d and 55 those of the cylinders $c' c'$ by a pipe d' . The pipes d and d' communicate with the pressure-reservoir w at either end of the same by means of pipes d^2 , in which are mounted back-pressure valves i and i' , one at either end of the 60 reservoir or between it and the cross-pipes d and d' at any suitable point, Fig. 1. At either side of the central pipes d^2 pipes $b b$ communicate from the pipe d to the forward ends of the two cylinders $c' c'$, while similar pipes h 65 communicate from the cross-pipe d' to the forward ends of the two cylinders $c c$. The forward ends of all four cylinders communicate with the open air by means of valves u and u' , arranged below the openings $n n$, Figs. 70 1 and 3. Above the said openings $n n$ of the forward end of each cylinder a back-pressure valve $o o'$ is mounted. The valves $u u'$ are advantageously positively operated, being held normally closed by a spring j and being 75 opened at the required moment by means of a pawl q' , pivotally connected to a frame q , fixed between the ends of the open pipes of two opposite cylinders. The pawls q' are alternately operated by means of a sliding arm 80 p , parallelly guided in bearings p' , mounted on the frame q , said slide-arm being worked by an eccentric e on the shaft s' and its eccentric-rod e' , which engages at the center or thereabout of the slide rod or arm p , being 85 pivotally connected thereto. The reservoir w is provided with an outlet m for the compressed air and a safety-valve v of the ordinary construction.

The engine operates in the following manner: If the pistons of all the cylinders are moved in a direction toward the shaft s' , air will pass by suction into the rear ends of the cylinders $c c$, through the valves $u' o'$, along the pipes b and d and to the front ends of the 95 cylinders $c' c'$, direct through the valves u' and openings n . At the front ends of the cylinders $c c$ and the rear ends of the cylinders $c' c'$ the air will be compressed, passing from the former along the pipes h , d' , and d^2 100 into the reservoir w and from the latter directly along the pipes d' and d^2 and through the valve i' . On the opposite stroke of the engine air will be drawn by suction into the front ends of

the cylinder $c c$ and the rear ends of those $c' c'$ in the first case through the valves $u u$ direct to the said cylinders and in the second case through these valves along the pipes h and d' , while air will be compressed in the front ends of cylinders $c' c'$ and in the rear ends of the cylinders $c c$, in the former case passing along the pipes $b b d$ through valve i and pipes d^2 into the opposite end of the reservoir w and in the second case directly along the pipe d through valve i and pipes d^2 . Thus will it be seen that the arrangement of pipes is such that each set will act alternately as suction and pressure set, which is the object of the invention.

I claim as my invention—

1. In an air-compressing engine the combination of four cylinders arranged in pairs, the front ends of the pairs facing each other and the cylinders in one pair opposite to and in line with a cylinder in the other pair, pistons in the cylinders, two piston-rods connecting the pistons in the opposite cylinders, means for rigidly connecting the two piston-rods and for reciprocating the four pistons simultaneously, pipes placing one end of each cylinder in communication with an end of the cylinder opposite, valve-controlled air-inlets to admit air into said pipes, a pressure-reservoir, and valve-controlled communica-

tions between the reservoir and pipes, whereby air is admitted to the suction ends of the four cylinders and expelled from the pressure ends simultaneously.

2. In an air-compressing engine, the combination of four cylinders arranged in pairs, the front ends of the pairs facing each other and the cylinders in one pair opposite to and in line with a cylinder in the other pair, pistons in the cylinders rigidly connected and means for reciprocating the same, four pipes, each communicating with the rear end of one cylinder and extending toward the opposite cylinder, air-inlet valves in the free ends of said pipes, a check-valve in each of said pipes opening toward the cylinder with the rear end of which it communicates, communications between said opposite cylinder and the said pipes at a point in the latter between the valves above mentioned, a pressure-reservoir, valve-controlled connection between the reservoir and the said pipes and means for positively actuating the air-inlet valves.

In witness whereof I have hereunto set my hand in presence of two witnesses.

GEORG SZIMAY.
